(57) **CLAIM**

The ornamental design for a sewing machine, as shown and described.

DESCRIPTION

FIG. 1 is a top plan view of a sewing machine;
FIG. 2 is a front view of the sewing machine;
FIG. 3 is a left side view of the sewing machine;
FIG. 4 is a right side view of the sewing machine;
FIG. 5 is a rear view of the sewing machine; and,
FIG. 6 is a perspective view of the sewing machine.
The broken lines which define the bounds of the claimed
design form no part thereof.
